 Filed Oct. 13, 1965, Ser. No. 495,435
 3 Claims. (Cl. 126—369)

ABSTRACT OF THE DISCLOSURE

A vessel having a longitudinal body shell, said body shell including a steam pressure chamber and a condensation chamber, said chambers being tandemly arranged, said condensation chamber being at atmospheric pressure when said pressure chamber is above atmospheric pressure, partition means sealingly separating said chambers, and condensation means mounted within said condensation chamber, said condensation means having an inlet and an outlet opening, one said opening being in communication with said pressure chamber, the other said opening being in communication with the atmosphere, and valve means for regulating fluid flow through said condensation means.

This invention relates generally to steam pressure vessel apparatus and more particularly to the combination of such apparatus with condensation means adapted to preclude discharge of steam directly to the atmosphere.

More specifically, the primary object of this invention resides in the provision of pressure and condensation chambers, both of which are formed integrally of a common longitudinal body shell.

Another object of the instant invention is to provide an apparatus which includes a pressure and a condensation chamber both housed within a longitudinal jacket.

A further object of the present invention is to provide apparatus of the foregoing character which is capable of substantially obviating the discharge of steam into the atmosphere and in so doing making possible the reuse of water which would otherwise be lost.

Another general object of this invention resides in the provision of sterilization or cooking apparatus as described herein which is economical of manufacture and highly efficient in use.

Other objects and advantages of the present improved pressure apparatus will be set forth in part hereinafter and in part will be obvious herefrom, or may be learned by practice of the invention, the same being realized and attained by means of the structure defined and pointed out in the appended claims.

The accompanying drawings referred to herein and constituting a part hereof, illustrate embodiments of the invention, and together with the description, serve to explain the principles of the invention.

FIGURE 1 is a side elevational view of the preferred embodiment of the invention;

FIGURE 2 is a top plan view thereof;

FIGURE 3 is a view of the invention taken along line 3—3 of FIGURE 1;

FIGURE 4 is a front elevational view of the invention; and

FIGURE 5 is a modified embodiment of the invention.

In accordance with the foregoing, the instant invention is essentially directed to the novel arrangement and combination of a pressure chamber and a condensation chamber, both chambers being included within a common longitudinal body shell illustrated in the accompanying drawings.

With reference to FIGURE 1, the vessel shown is comprised of a longitudinal body 1 which includes the

2

outside shell 2 of steam pressure chamber 4 and condensation chamber 6. It will be understood that the pressure condensation chambers, may within the contemplation of this invention, be separate although joined whereby 5 the outer shells thereof will become united to form a continuous longitudinal body shell. Or as will be described hereinbelow following with respect to FIGURE 5, the chambers may be arranged in tandem, a separate outer longitudinal body shell being applied about the pressure chamber and extending therefrom to form the shell of the condensation chamber.

Pressure chamber 4 is provided with a door 8 which may be of any suitable construction, and a heating element 10 is located on the bottom of the chamber. In 15 operation the heating element 10 serves to generate steam by heating water in which it is immersed. An outside steam source, however, may be utilized wherein the use of a self contained heater would not be required.

The condensation chamber 6 is provided with an 20 opening 12 where through water may be poured to fill the chamber. A door 14 is shown with apertures 16 therein, said door, inter alia, serving to silence the noise occasioned when steam enters the chamber as described hereinbelow. Wall 18 partitions the chambers, and may be a single 25 common wall as shown in FIGURES 1 and 2 or may be formed of two separate walls in the event chambers 4 and 6 are separate but united to form a continuous longitudinal body structure. Two separate partition walls with insulation material, a vacuum or dead air therebetween 30 may also be used to separate the chambers.

Condensation coil or condensation means 24 is mounted within the condensation chamber 6. Said condensation means may be a tubular coil as shown nor any other suitable condensing unit which effectuates heat exchange 35 between steam or other fluid passing therethrough and the ambient medium. The coil illustrated is provided with an inlet opening 26 and an outlet opening 28, the inlet opening being in communication with the pressure chamber 4 as shown and the outlet opening being in communication with the atmosphere as shown. Valve 30 is connected as shown to said condensation coil to enable positive shut-off of fluid flow through said coil between said pressure and condensation chambers. Valve handle 32 enables the user to regulate the fluid flow rate through 40 the valve. Stand 34 is provided to support the vessel.

With reference now to FIGURE 5 of the drawings, the alternate embodiment of the invention illustrated therein includes pressure and condensation chambers 36 and 38, respectively, longitudinal body shell 40 being superposed around pressure chamber 36 and a portion of 50 said body shell being arranged to extend beyond said pressure chamber to form the side wall of said condensation chamber. Said extending portion of said body shell is closed by end wall 42, the latter being spaced from wall 55 20 of said pressure chamber.

In operation, the pressure chamber is filled with a predetermined quantity of water, valve 30 being in the shut-off position. The door 8 is closed and heater 10 is energized. The water within said chamber will boil and 60 transform to steam to build up pressure within chamber 4. Upon termination of the sterilization or food cooking period, valve 30 is turned to the open position whereupon steam and remaining water will pass through coil 24, which is preferably submerged in water, and the 65 steam will be transformed to the liquid state. The liquid thus formed will be added to the water previously present in the condensation chamber. After the steam has been discharged from the pressure chamber, valve 30 is closed. Should it be desired to re-fill the pressure chamber, the 70 valve, when opened, will permit water to flow through the coil and into the pressure chamber. Thus, the water pre-

viously condensed may be reused for subsequent pressure cycles.

Although exemplary embodiments of the combined pressure-condensation chamber apparatus have been described, it will be understood that within the purview of this invention various changes may be made in the forms, details, proportions, instrumentation of the vessel and arrangement of parts, the combination thereof and mode of operation, which generally stated consists in a device capable of carrying out the objects set forth, as disclosed and defined in the appended claims.

What is claimed is:

1. A vessel comprised of a longitudinal body shell, said body shell including a steam pressure chamber and a condensation chamber, said chambers being tandemly arranged, said condensation chamber being at atmospheric pressure when said pressure chamber is above atmospheric pressure, partition means sealingly separating said chambers, condensation means through which fluid can flow, said condensation means being mounted within said condensation chamber, said condensation means having an inlet and an outlet opening, one said opening being in communication with said pressure chamber, the other said opening being in communication with the atmosphere, and valve means for regulating fluid flow through said condensation means.

2. A vessel as set forth in claim 1 wherein said pressure and condensation chambers are integrally formed of said longitudinal body shell.

3. A vessel comprised of a longitudinal body shell,

said body shell including a steam pressure chamber and a condensation chamber, said chambers being tandemly arranged, said condensation chamber being at atmospheric pressure when said pressure chamber is above atmospheric pressure, condensation means through which fluid can flow, said condensation means having an inlet and an outlet opening, one said opening being in communication with said pressure chamber, the other said opening being in communication with the atmosphere, and valve means for regulating fluid flow through said condensation means, said pressure chamber being at least partially superposed by said longitudinal body shell, a portion of said shell extending beyond said pressure chamber, said end wall and extending portion forming an end and sides of said condensation chamber.
